UNITED STATES PATENT OFFICE

CLARK T. MORSE, OF DETROIT, MICHIGAN, ASSIGNOR TO AMERICAN BLOWER CORPORATION, OF DETROIT, MICHIGAN, A CORPORATION OF DELAWARE

FAN HOUSING CONSTRUCTION

Application filed January 27, 1931. Serial No. 511,569.

My invention relates to fans and particularly to the construction of the housing therefor and the support of the housing.

The requirements for a successful fan housing are cheapness, ease in manufacturing, great rigidity without vibration, simplicity of assembly, accuracy and adaptability of construction to any position, or location, with a firm support for the bearings of the fan shaft, and perfect alignment of the fan with respect to its casing with which it is usually associated in very close and accurate relationship.

It is an object to provide such a construction employing a ring, a shaft support in the ring which reenforces the ring at the same time it accurately supports the shaft on which the fan is mounted; the attachment of the ring to the fan housing and the support of the fan housing from the ring are in such a manner that the support may be located any place around the ring.

Referring to the drawings:

Figure 1 is a side elevation;

Figure 2 is an elevation of Figure 1 from the discharge end of the fan;

Figure 3 is a section on the line 3—3 of Figure 1;

Figure 4 is a section on the line 4—4 of Figure 1.

Referring to the drawings in detail, 1 designates the scroll of sheet metal forming the exterior wall of the fan casing. This scroll terminates at the top and bottom adjacent to the frame 2 through which the air may be exhausted from the multi-bladed fan 3 which is carried on the transverse shaft 4 in the bearings 5 and 6.

The air enters the fan through the eye 7 and is guided therein to the fan by the annular Venturi shaped inlet passageway ring 8, the outer margin of which is formed into an angular flange 9 that is either welded or bolted to a similar flange 10 on the ring 11. The ring 11 is welded at its juncture line with the side 12 of the fan housing which may be either bolted or welded to the scroll portion of the housing 1. Between this ring 11 and the periphery of the side wall 12 are a number of plate ribs welded to the ring

at their ends and to the side walls 12 on their sides, such ribs being designated as 13, 14, 15 and 16.

Bolted by the bolts 17a, 18a, and 23a to the periphery of the ring 11 are the bracing legs 17 and 18 which are provided with feet portions 19 and 20 and diagonal brace portions 21 and 22 which are joined on a ring supporting portion at 23 in association with the rib 15. Four sets of bolt holes are made in the ring at equidistant points on the periphery, three sets being used at one time. It will be noted that the entire structure, consisting of portions 17, 19, 22, 23, 21 and 18, is formed of a single piece of flat metal, but may be made of multiple pieces. The points of attachment of the portions 17 and 18 to the ring 11 are adjacent the ribs 14 and 16 and also adjacent the points of attachment of the cross support 24 for the bearings, either 5 or 6. On either side of the bearings beneath the cross support 24 are vertical supports 25 and 26 which are welded at one end to the cross support 24 and at the other end to the inlet Venturi ring 8 just as the ends 24 are welded to the venturi 8. The points of attachment of the vertical supports 25 and 26 to the ring 8 are adjacent to points where the braces 22 and 21 engage the exterior of the ring 11. Thus, a truss structure is formed of cheap, flat, easily formed metal which can be welded together arranged in any desired configuration, thickness or width without the use of a special fixture, jig, tool or die and with the complete elimination of castings. The leg support and reenforcing can be arranged at any point around the periphery of the ring 11, although preferably in the position shown and the fan housing can be supported with its fan in any desired position. By the use of a concentric reenforcing supporting ring and the Venturi ring, I provide at one operation and with one assembly an inlet passageway for the air and a reenforcing support therefor with the minimum of width of the fan housing.

By utilizing the combination of ring 11 about the inlet opening and the ribs 13, 14, 15 and 16, as well as the supporting mem-

bers 17, 22, 21 and 18, all of which are welded to the surface of the side wall 12, it is possible to use a relatively thin sheet for the side wall 12 which will have great rigidity and be equivalent to a very thick and expensive and difficult piece of metal. All tendencies to vibration, hum and other disagreeable noises will be thus eliminated.

It will be further noted that the fan, its bearings and shaft ring directly upon the supporting surface, such as the floor or the wall, through this support arrangement do not have a tendency to transmit the movement and vibrations of the fan to the fan housing.

I will be understood that I desire to comprehend within my invention such modifications as may be clearly embraced within the scope of my claims and invention.

Having thus fully described my invention, what I claim as new and desire to secure by Letters Patent, is:

1. In a blower casing, the combination of end walls and side walls, a plurality of reinforcing strips attached on their inner edges to the side walls and projecting laterally therefrom, a ring connecting the inner extremities of said strips, said ring being attached to the side wall in which it is located, and means for supporting a fan shaft bearing in said ring, said ring, strips and side walls being integrally welded to one another, and a separate supporting means for supporting said casing, fan shaft and fan in spaced relation from a base surface, consisting of a member selectively positioned and attached to the opposite sides and bottom of the ring.

2. In a blower casing, an end wall and side walls, a plurality of radially disposed sheet metal plates welded on their inner edges to the outer surface of the side walls, and a ring connecting the inner ends of said metal plates to one another and to the side walls, a bearing support detachably supported in said ring, and a separate supporting means for supporting said casing, fan shaft and fan in spaced relation from a base surface, consisting of a member selectively positioned and attached to the opposite sides and bottom of the ring, said supporting means having a plurality of vertical, horizontal and diagonal portions forming an inverted M.

3. In combination, a casing having end walls, side walls and diagonally disposed braces consisting of plates at right angles to the side walls, the inner edges of the plates being welded to the side wall surfaces, rings supported by the inner ends of said plates and said side walls, bearings mounted in said rings, a fan and fan shaft carried on said bearings, and transverse supporting plates bisecting a portion of said rings for supporting said bearings, one of said bisecting plates having a vertical support between it and the ring, and a separate supporting

means for supporting said casing, fan shaft and fan in spaced relation from a base surface, consisting of a member selectively positioned and attached to the opposite sides and bottom of the ring, said member having the shape of an inverted M.

In testimony whereof, I affix my signature.

CLARK T. MORSE.
